UNITED STATES PATENT OFFICE.

ALBERT LATHAM, OF BEVERLY, MASSACHUSETTS, ASSIGNOR TO AMERICAN BUTTON & FASTENER CO., OF AUGUSTA, MAINE, A CORPORATION OF MAINE.

MACHINE FOR OPERATING UPON FASTENINGS.

Application filed June 26, 1920. Serial No. 391,908.

My invention relates to machines for operating upon fastenings, and more particularly to those adapted for the attachment of such fastenings as buttons to shoes, gaiters and the like, by staples or similar attaching devices.

Objects of the invention are to provide a simple and durable machine of this character, in which the devices operated upon are delivered regularly and with certainty, assembled by positively acting mechanism, and presented in correct relation to the work.

In the attainment of these objects, a feature of the invention consists of supplying means for fastening devices and fastening-attaching devices, said supplying means co-operating to permit the devices to be assembled, together with means for moving the assembled devices to prepare for their advance from the assembling position. This positioning preferably suitably aligns the devices to be acted upon by means which conveys them forward for attachment to the work, if the invention is applied to the setting of the fastenings, or, as an instance of another utilization, may advance them to a magazine tube, which may later be applied to an independent attaching machine. In the illustrated embodiment of the invention, a raceway delivers a button with its eye across a staple raceway to receive a leg of the staple, which button is thereafter turned, preferably by grasping it, in the direction of a guideway through which it is to be advanced.

Another feature of the invention may be found in a stop lying in the paths of both fastening devices and attaching devices delivered by converging raceways. To provide for the forward travel of the devices, a portion of the stop may be movable out of said paths independently of the other portions of the stop. This organization insures a correct assembling of the fastening and attaching devices. As disclosed, the stop is rotatable, and the portion movable from the paths of the devices may be reciprocal. In the rotation of the stop, it may be arranged to grasp the fastening, and may then perform the positioning function already indicated.

As a further feature of the invention, I may impart, in a novel manner, to the member which advances the fastening and at-

taching devices a plurality of movements for each pair of devices advanced. One of these movements may effect the assembling, while another carries the devices forward from the assembling position. These movements are preferably reciprocatory, there being a travel forward for the assembling effect, followed by a withdrawal to allow a positioning of the assembled devices, and then a longer reciprocation to bring about their advance. As herein illustrated, these movements are produced by separate actuating mechanisms acting at periods predetermined in the operation of the machine, with provision for lost motion in the connection between one of the driving mechanisms and the advancing means to permit the actuating effect to be exercised without interference.

Other features will be developed in the following description and claims, and are illustrated in the accompanying drawings, in which

Figure 1 is a top plan view, with parts broken away, of a particular embodiment of the invention;

Fig. 2 is a broken front elevation thereof;

Fig. 3 is a side elevation looking from the right in Fig. 2, with portions broken away and omitted;

Fig. 4 is a broken elevation of the opposite side of the machine;

Fig. 5 illustrates diagrammatically various positions of the driving or advancing member and its actuating mechanism;

Fig. 6 is an enlarged front elevation of the elements co-operating more directly with the fastening and attaching devices;

Fig. 7 is a side elevation thereof;

Figs. 8 and 9 are transverse sectional details on the lines 8-8 and 9-9 of Figs. 6 and 7, respectively, illustrating the button and staple raceways.

Figs. 10, 11 and 12 show successive positions of the stop and advancing mechanisms;

Fig. 13 is a perspective view of the stop and positioning mechanism;

Fig. 14 shows in perspective the connecting portion between the stop-actuating sleeves;

Fig. 15 is a detail in elevation of the mechanism for rotating the stop;

Fig. 16 illustrates in sectional perspective the button-feeding device;

Fig. 17 is a central vertical section therethrough; and

Fig. 18 is an enlarged sectional detail taken through one side of the feeder.

- 5 The illustrated machine is designed to attach buttons by means of staples passed through the button eyes and set in the work. For this purpose there is mounted upon a frame 10 a staple raceway 12 and a button raceway 14, inclined downwardly toward each other and shown as separated by an angle, considered in a horizontal plane, of about 90 degrees, these raceways converging to a stop and positioning mechanism 16. 10 Supported at one side of the frame upon brackets 18, 18 and alined with the staple raceway 12 is a magazine bar 20, which may be loaded with staples and applied to the present machine to supply the raceway. To hold the magazine bar in correct alinement with the raceway, a retaining plate 22 is secured to the latter and extends over the side of the former, the magazine bar entering between this plate and the side of the frame when it is applied to the brackets 18 15 and pressed down into co-operation with the raceway. Both the raceway and magazine include bars 24 of such width that they may be straddled by the staples, and having at the center of their upper side a rounded rib 26 adapted to engage the depression ordinarily formed at the middle of staple yokes. To prevent displacement of the staples upon the magazine and raceway by the jar- 20 ring of the machine, a cover-plate 28 extends above them, being clamped between the raceway 12 and magazine 20 and the frame. The button raceway consists of an inclined slot 30 extending laterally in a horizontal direction and serving to receive the button eyes, while a groove 32 formed just below this co-operates with the heads of the buttons. One wall of the groove 32 is furnished by an extended depression in the frame, while the opposite wall is provided by a plate 34 attached to the frame by screws 36 passing through vertical slots 38 in the plate. The slotted connection of the plate to the frame permits the vertical adjustment 25 of the former, thereby changing the relation between the head groove and the eye slot, so that the buttons may rest properly therein to travel down the raceway without clogging. 30 The raceway 14 is supplied with buttons by a feeder 40. This may include a hopper 42 attached to one side of the upper portion of the frame, and having an inclined bottom wall delivering through a throat 44 into a cylindrical container 46. Surrounding the upper portion of the container and joined to the upper end of the button raceway 14 35 is a receiver or guideway 48, the inner wall of which is furnished by the reduced upper edge 50 of the container. The outer wall

may consist of a cylindrical casing 52 curved inwardly at 54 over a shoulder at the top of the container into proximity with the wall 50. There is thus formed an annular groove in which the button heads will rest for movement with relatively slight friction, and with the button eyes overlying the top of the edge 50. To so arrange this eye-engaging edge to the groove that the buttons may be supported to the best advantage for their travel along the raceway, the depth of the groove may be varied by raising or lowering the casing by means of a screw 56 threaded through a lug 58 projecting outwardly from the top of the casing and contacting with a bracket 60 formed upon the frame. To guide the casing in its movement of adjustment, there is provided a pin 62 rising from the top of the bracket and extending through an opening in the lug 58. Obviously, if buttons with heads of small diameter are to be fed, the casing will be raised so that the bottom of the groove will lie nearer the top of the edge 50 than if the heads are of greater diameter. 90

To transfer buttons from the mass in the container to the receiver, elevating or carrier members in the form of pins 64 are movable through a circular series of openings 66 in the outer portion of the bottom of the container, toward which openings this bottom wall is inclined at 68. The pins are respectively fixed to the upwardly extending arms of a corresponding series of bell-crank levers 70 having pivot-pins 72 movable through pairs of radial, horizontal slots 74 near the periphery of a supporting member or head 76. This head is fixed upon the lower extremity of a vertical rod 78 passing through the bottom of the container, and carried by an arm 80 secured at the upper end of a bar 82 arranged to reciprocate vertically in ways in the frame. The bar contains in its lower portion a transverse opening 84 to receive the rounded end of a lever 86 pivoted at 88 upon the frame. Articulated to this lever is a link 90 turning upon the pin of a crank-disk 92 carried upon the end of a short shaft 94 journaled transversely at the bottom of the frame. This shaft is connected by spiral gearing 96 with a longitudinal shaft 98, which in turn is united by spur gearing 100 with a parallel shaft 102. The shaft 102 is connected by spiral gearing 104 to a main driving shaft 106 receiving power through a single-rotation clutch 108 from a pulley 110 rotated from any suitable source of power. As the crank-disk 92 turns, it oscillates the lever 86 and reciprocates the bar 82, thus raising and lowering the head 76. Raising the head causes the pins 64 to be carried upwardly from their normal position illustrated in Fig. 16 of the drawings, in which the reduced points are just below 110 115 120 125 130

the tops of the openings 66 in the bottom of the container to the positions appearing in Fig. 17, in which said points are above the upper edge of the wall 50. In thus rising, a certain number of the pins will enter the eyes of buttons lying in a body in the bottom of the container, and elevate them to points above the receiving groove 48. Each of the bell-cranks 70 has a horizontal arm rounded at 112, this portion of the lever being pressed by a spring 114, located in a horizontal recess 116 in the head, against the smooth interior surface of a sleeve 118 movable vertically within a downward cylindrical extension 120 of the container. The travel of this sleeve from the container is limited by a flanged ring 122 screwed upon the bottom of the extension 120; while its upward movement is arrested by a pin 124 depending from the bottom of the container. Formed at the inner top portion of the sleeve 118 is an annular cam 126 having a lower inclined surface 128 and above this a depression 130. As the head is raised and the bell-crank levers 70 approach the top of the sleeve 118, which is now resting upon the ring 122, the ends 112 of the levers ride over the surface 128, and are by this contact swung outwardly so that they are shifted from their normal vertical position to the inclined relation shown in Fig. 17 of the drawings, in which the points are above the button-receiving groove 48. The frictional engagement of the levers with the cam raises the sleeve with the head until the former is stopped by contact with the pin 124. The levers now pass over an elevation or ridge 131 between the surface 128 and the depression 130, and snap sharply into said depressions under the influence of the springs 114. This quick lateral movement of the ends of the pins, accentuated in effect by their striking against the wall 50, causes the heads of all the buttons carried by the pins to be turned outwardly so that they are located above the receiving groove. Then, as the head descends, the sleeve 118 first moves with it with the ends 112 of the levers remaining in the depression 130, maintaining the outward position of the pins and elevated buttons until the latter are doffed from the pins by contact with the wall. This having been accomplished, the sleeve strikes the stop-ring 122, and the movement of the head continuing, the levers 70 ride out of the depressions, straightening the pins, which continue their movement to the normal position.

For the purpose of conveying buttons from the receiving guideway 48 into the raceway 14, I provide a member revoluble over said guideway and movable into and out of co-operation therewith. Preferably, this member is operable with the elevating pins. To this end, there is formed upon the

rod 78 a helix 132, and surrounding this is an internally threaded plate 134. The plate bears upon its upwardly and outwardly inclined periphery 136 a series of groups of bristles or like flexible members 138, the ends 70 of which lie above the guideway. The downward movement of the plate 134 is limited by a vertical sleeve 140 located at the center of the bottom of the container and serving also as a guide for the rod 78. As the elevating pins are raised by the head, the brush member 138 is carried away from the guideway by the cylindrical portion of the rod at the lower end of the helix. But when, in the downward movement of the rod, the plate 75 strikes the upper extremity of the sleeve 140, the helix, traveling through the threaded portion of the plate, causes its rotation. At this time the path of the bristles lies within the guideway, so that they contact with the 80 buttons which have been deposited therein upon the lowering of the pins, and these bristles, revolving in a counter-clockwise direction, as viewed from above, sweep the buttons along the guideway into the raceway, 85 which merges tangentially into said guideway.

The leading button in the raceway contacts with the stop and positioning mechanism 16. Extending into the path of the button eyes at the end of the raceway slot 30 is the reduced end of a spindle 142 having a bearing in surrounding sleeve sections 144 and 146 journaled in the frame. The section 144 adjacent to the raceway surrounds somewhat 90 less than half the spindle for a portion of its length, while beyond this, at 148, the sleeve 144 completely encircles the spindle, it having a reduced portion at 149. The inner end of the sleeve 144 has an annular flange 150 95 bearing against a wall of the frame to prevent outward movement of the sleeve. The section 146 is similar in form to the outer portion of the section 144, being less than semi-cylindrical, but, in this case, for its entire length, it bearing upon the reduced portion 149 of the companion sleeve, and at its outer end being spaced from the latter at 152. This arrangement allows the section 146 to rotate relatively to the section 144, so 100 that the opposite walls of the space 152 may approach one another and serve as jaws to grasp a button eye, exerting pressure on its opposite sides. A collar or flange 158 at the inner end of the section 146 holds it against 105 outward movement similarly to the collar of the companion section. Rotation imparted to the section 146 is against the resistance of a friction-plug 160 movable toward and from the sleeve in an opening in the frame, 110 and being pressed into contact with said sleeve by a spring 162. This spring at its outer extremity contacts with a screw 164 closing the frame opening, and permitting, 115 by variations in its position, a change in the 120

4

force exerted by the spring and the friction imposed upon the sleeve section by the plug. Surrounding the spindle 142 beyond the sleeve sections 144 and 146 is a sleeve 166 connected with the sleeve 144 for longitudinal separation by co-operating projections and depressions 168. Beyond this sleeve 166 along the spindle is still another sleeve 170 having a bearing in the frame, and connected for rotation with the sleeve 166 by pairs of opposite lugs 172, 172 projecting from collars 174, 174 fast upon the sleeves. Threaded through one of the lugs of each pair is a screw 176, and by adjusting the positions of these screws the time and extent of rotation communicated from the sleeve 170 to the sleeve 166 may be altered. The sleeve 170 is capable of movement to the left (Fig. 3), being held in engagement with the sleeve 166, so that the projections and depressions 168 are maintained in co-operation, by a finger 178 depending from a slide 180 into a groove 186 in the collar. The slide is fixed in position upon the frame by a screw 182 passing through a horizontal slot 184 in the slide. If it is desired to remove the button-engaging portions of the sleeve sections 144 and 146 because of a change in the size of the buttons operated upon, or for any other reason, the slide 180 may be moved to the right (Fig. 3), carrying with it the sleeve section 170. The spindle may now be withdrawn from the sleeves, and the sleeve 166 separated laterally from the sections 144 and 146, there having been room created by the movement of the sleeve 170 to free the projections and depressions 168 by a longitudinal movement of this sleeve 166. This leaves the sections 144 and 146 entirely free to be drawn inwardly from their bearing in the frame. Fast upon the sleeve 170 is a pinion 188, the teeth being elongated along the sleeve to allow the sleeve-travel just described. With this pinion meshes a gear-segment 190 carried at one extremity of a bell crank lever 192 pivoted at 194 upon the frame. At the opposite end of the lever is a lateral projection 196, preferably bearing an anti-friction roll and entering a cam-groove 198 formed in the inner face of a cylinder 200 secured to the shaft 98. This cam, acting through the lever and gearing, produces an oscillation of the sleeve portions 144, 146, 166 and 170, carrying the space 152 between the sections 144 and 146 from normal alignment with the slot 30 of the button raceway into a vertical position alined with the rib 26 of the staple raceway and with associated elements hereinafter described.

Upon the spindle 142 outside the pinion 188 are circular rack-teeth 202, which are engaged by a gear-segment 204 formed upon an arm 206 secured upon the upper extremity of a vertical spindle 208 mounted to turn in the frame. At the bottom of the spindle

is fixed an arm 210 having a projection 212 entering a cam-groove 214 in the periphery of the cylinder 200. The effect of this cam and the connecting elements actuated thereby is to carry the outer end of the spindle 142 inwardly from a position in which a longitudinal groove 216 in one side is opposite the button raceway, through a distance such that the space 152 between the sleeve sections is entirely freed for the movement of the button eyes through it. The spindle is, in addition to its reciprocation, rotatable with the surrounding sleeves, its groove 216 receiving internally projecting portions of the sections 144 and 146, there being, however, provision for some circumferential play, to allow the relative movement of the sections.

The staple raceway 12 terminates just at the rear of a vertical passage 218 in a head 219 of the frame, the last staple of the series depending from the raceway being held in this passage against downward movement by a detent or retaining member 220, the end of which projects just into the passage for engagement by the staple. This detent is guided in a slot in the frame, and has a stem 222 projecting through an opening therein. Surrounding this stem is a spring 224, which acts to hold the detent yieldably in the passage, and upon the outer extremity of said stem are nuts 226 variable in position to adjust the normal position of the detent. When pressure is exerted upon the top of the staple held by this detent, as is now to be described, said detent will be thrust back against its spring, thus clearing the passage for the advance of the staple. Guided in the passage or way 218 is a staple-advancing member 228, this being in the present instance a driver adapted to set the staples in the work, it having an end curved at 230 to conform to the staple yoke. At its upper end the driver is attached to a slide 232 movable in ways 234 above the passage 218. The slide has formed in one edge a rack 236, with which meshes a pinion 238 fast upon a tubular shaft or sleeve 240, this sleeve being secured upon a shaft 242 journaled near the top of the frame. A spiral spring 244 is situated in a casing about the rear end of the shaft 242, and is connected to said shaft at its inner convolution and to the casing at 248. This spring tends, by the tension it exerts upon the shaft, to maintain the driver in a raised position. The force of the spring may be changed by an adjustment of the attaching point 248 circumferentially of the casing, this being effected by the screw 250 passing through an opening in the casing head and engaging any one of a circular series of openings in a flange 251 projecting from the edge of the casing. The sleeve 240 has at its inner end an enlargement or flange, from which is a projection

252 extending along the shaft. This is arranged to enter a circumferentially extended recess 254 in an adjacent enlargement or flange from a tubular shaft or sleeve 256 surrounding the shaft 242 and loose thereon. The sleeves 240 and 256 have secured upon them pinions 258 and 260, respectively. With the pinion 258 meshes a vertical rack-bar 262 arranged to slide in the frame 10 and being divided at 264, so that it is in two sections independently movable. A rack-bar 266 engages the pinion 260. These rack-bars serve as connectors between the operating shaft 242 of the driver bar and its 15 driving mechanism, which includes actuating crank-disks 268 and 270 for the bars 262 and 266, respectively. The crank-pin 272 of each disk has a block 274 sliding in ways 276 in transverse extensions of the bars. The revolution of the pins causing the blocks to travel in the ways and reciprocate the bars. The disk 270 is fixed upon the end of the driving shaft 106; while the disk 268 receives motion from a shaft 278 driven 20 by spiral gearing 280 connecting it with the shaft 102. These connections rotate the crank-disks in opposite directions and with the disk 268 moving at double the speed of the disk 270. It is observed, that while the reciprocation of both the bars 262 and 266 will cause, through the sleeves which they actuate, the rotation of the shaft 242, in the same direction, the movement imparted to the bar 228 will be in the opposite 25 direction to that of the connecting bars. That is, when the latter move up, the former moves down, and vice versa. With the driving mechanism in its normal position, the bar 228 is held at its point of greatest elevation, this being indicated at *w* in Fig. 5 of the drawings; the crank-pins of the disks 268 and 270 occupy the positions designated as *a* in this figure. At this time the sections of the bar 266 are in contact 30 at 264; and the projection 252 of the sleeve 240 is situated at the bottom of the slot 254, as viewed in Fig. 4. When the action of the driving mechanism begins, the high-speed crank-disk 268 in traveling from its initial point, which is shown as about 15 degrees above the horizontal, to the upper center at *b*, lowers the bar 228 at a relatively rapid rate to the point *x*, so that it contacts with the terminal staple held by the detent 220, pressing this down by pushing the detent to one side, and, as this angle *b* of the crank-disk is attained, forcing one leg through the eye of the terminal button 35 which is positioned in the space 152 of the stop device and held against downward movement by the spindle 142. The staple is now astride the spindle, held against lateral movement thereby. This being accomplished, continued movement of the disk 168 to the point *c* quickly withdraws the bar 228 to *y* so that the staple and button eye are freed. At this time the rotation of the sleeve sections 144 and 146 occurs, as previously described, the section 144 in its movement forcing the button eye against 40 the frictionally restrained section 146 to grasp it and then turn it about an axis extending through both the head and eye until said eye is aligned with the axis of the passage 218 and with a guideway 281 45 extending vertically in the head 219 below the stop device. During this insertion of the staple in the button eye under the influence of the crank-disk 268, the more slowly moving actuating mechanism, including the disk 270, is allowed to operate independently and without interference by the travel of the projection 252 in the recess 254. In the position *c* the projection will have reached the end of the recess, and the 50 driving mechanism 270 comes into action. It has up to this time risen from the lowest center *a* to the point *c*, about 55 degrees above this. It now, in moving to the point *d*, lowers the bar 228 to *z*, more slowly than 55 in the movement just described under the influence of the disk 268, to carry the driving end of the bar against the staple and move this and the engaged button eye downwardly through the passage 281 to the setting point. In the operation, the staple travels within the passage, while the button head is outside, its eye passing through a central slot 283. While this is going on, the pin at the rapidly rotating 60 crank-disk 268 is first descending, this independent movement being allowed by a separation of the sections of the bar 262 at the division 264, and then from the lower center rising to the initial point 65 *a*, this being reached when the pin of the disk 270 is at the point *d*. The effect of this last-mentioned disk upon the bar 228 still continues as the crank-pin travels from 70 the upper center *d* to the lower center *a* to raise the bar to its normal position *w*. During this action the disk 268 makes a complete idle rotation, interference being avoided by the separation of the bar 262 at 75 264, and the movement of the projection 252 in the recess 254. At all times in the operation, the spring 244 tends to return the driver to its normal raised position and to take up the lost motion between the sleeve sections 240 and 256 and between the portions of the bar 262. The elements are now 80 at normal, ready for a repetition of the operation.

The work in which the staple is to be set is supported against the pressure of the driver-bar by an anvil 282 suitably recessed at 284 to deflect the legs of the staples toward each other for the purpose of clinching them in the work. This anvil is supported upon a bracket 286 projecting from 85 90 95 100 105 110 115 120 125 130

the side of a slide 288 arranged to reciprocate vertically in ways at the lower portion of the front of the frame. Mounted to move in the same direction as the slide, but at the rear, is a block 290 having at its lower portion a forwardly extending projection 292 upon which is supported a helical spring 293 bearing against a rearward projection 294 from the top of the slide. To prevent this spring from deflecting laterally under pressure, a pin 296 is fixed in the projection 292 and extends within the convolutions of the spring for a portion of its height. At the rear of the block 290 is a horizontal slot to receive a crank-pin 298 projecting from that spur-gear of the pair 100 which is carried by the shaft 98. The revolution of this crank-pin causes the block to be raised, and through the spring 293 the anvil is forced against the work to hold it yieldingly against the contact end 299 of the head 219. Thus the work is properly grasped and held for the setting operation, regardless of its thickness. To fix the anvil in position to receive the setting pressure, a lower surface 300 of the slide 288 is formed to cooperate with the upper inclined surface of a wedge 302 mounted to slide upon the base of the frame and having a rod 304 projecting from its inner extremity and guided in said frame. This rod passes through an opening in a lug 308 depending from a slide 310 movable horizontally in ways in the frame above the rod and reciprocated by a projection 312 entering a cam-groove 314 in the periphery of the cylinder 200. Surrounding the rod 304 between the lug 308 and the wedge, is a spring 316, and at the opposite side of the lug from the spring is an enlargement 318 upon the rod. The cam-groove is of such contour that, after the anvil has been raised into firm contact with the work by the spring 293, the spring 316 presses the wedge 302 yieldingly beneath the surface 300 of the anvil slide, furnishing a positive support for the slide and anvil to enable the latter to resist the pressure of the bar 228. After the setting operation, as the pressure upon the work by the anvil is relieved, the lug 308 contacting with the shaft at 318 withdraws the wedge so that the anvil may return to its initial lowered position.

To briefly outline the general operation of the machine, staples are supplied upon the magazine 20, and buttons are placed within the hopper 42. The staples sliding down the raceway 12 are held, with the leader ready for utilization, by the detent 220, while the buttons are elevated by the reciprocation of the pins 64, are moved outwardly by the lateral swing of the pins over the receiving guideway 48, and are positioned on said pins for delivery to the guideway 12 by the secondary abrupt oscillation under

the influence of the cam 126. When the pins are lowered, the buttons left in the guideway are swept into the button raceway 14 by the brush 138, and descend the raceway until the first button therein is stopped by contact with the spindle 142 and with its eye-opening in alinement with one of the legs of the staple supported by the detent in the driver passage. In attaching a button, the operator inserts the work which is to receive it between the anvil 282 and the contact end 299 of the head, and releases the clutch 108 so that the machine starts upon a single cycle of operations. In this, the anvil is raised by the crank-pin 298 to clamp the work against the head, and is locked to receive the setting pressure by the wedge 302. The driving bar 228 descends under the influence of the crank-disk 268, carrying down the lower staple and forcing back the detent 220, this movement continuing until the left-hand staple leg (Fig. 10) is within the button eye. The driver now rising sufficiently to free the staple, the stop mechanism is rotated by the gearing 188, 190, first grasping the button eye between the sleeve sections 144 and 146, and then revolving it thus held against play to the position illustrated in Fig. 11, in which the major transverse dimension of the eye extends in the same direction as the legs of the staple, being positioned for descent through the driving passage 281. While thus arranged, the stop portion of the spindle 142 is moved out of the path of the driver by the gearing 202 and 204; and said driver, actuated by the crank-disk 270, descends more slowly than in the assembling operation to effectively force the staple, with the button, down the passage 281 and into the work. Finally the driver is returned to its normal position: the space 152 of the stop mechanism is restored to alinement with the button raceway, while the spindle 142 is again projected; the locking wedge is withdrawn from the anvil slide and this is lowered; and the machine is ready for a repetition of the operation.

The button-feeding portion of this machine is made the subject of an application for Letters Patent of the United States, this application having been filed on August 4, 1925, bearing the Serial No. 48,084.

Having thus described my invention, what I claim as new and desire to secure by Letters Patent of the United States is:

1. In a machine of the class described, supplying means for a fastening device, supplying means for a fastening-attaching device, said supplying means co-operating to permit the fastening and attaching devices to be assembled, and stop means for moving the assembled devices to prepare for their advance from the assembling position.

2. In a machine of the class described, supplying means for a fastening device, supplying means for a fastening-attaching device, said supplying means co-operating to permit the fastening and attaching devices to be assembled, advancing means for the assembled devices, and means independent of the advancing means for placing the assembled devices in alinement with said advancing means. 75
3. In a machine of the class described, supplying means for a fastening device, supplying means for a fastening-attaching device, said supplying means co-operating to permit the fastening and attaching devices to be assembled, advancing means for the assembled devices, and means movable in the path of the advancing means for rotating the fastening device into alinement with the advancing means. 80
4. In a machine of the class described, supplying means for a fastening device, supplying means for a fastening-attaching device, said supplying means co-operating to permit the fastening and attaching devices to be assembled, means arranged to grasp one of the assembled devices and to move it preparatory to attachment, and means for causing such attachment. 85
5. In a machine of the class described, a staple raceway, a button raceway, mechanism into engagement with which the staples and buttons are delivered from the raceways, means for moving the mechanism to cause the legs of a staple and the major transverse dimension of a button eye to extend in the same direction, and means for advancing the thus arranged staple and button from the raceways. 90
6. In a machine of the class described, a staple raceway, a raceway arranged to deliver a button with its eye opening across the staple raceway to receive a staple, stop mechanism co-operating with both raceways and acting to turn the button eye in the direction of advance of the staple, and means for contacting with the staple to advance it with the associated button. 95
7. In a machine of the class described, a driver passage and a driver therein, a raceway arranged to deliver a button with its eye across the passage, a raceway arranged to deliver a staple with its legs extending longitudinally of the passage, means for advancing the staple through the button eye, and mechanism arranged to both hold the button eye to receive the staple and to turn said eye in the direction of the passage. 100
8. In a machine of the class described, a driver passage and a driver therein, a raceway arranged to deliver a button with its eye across the passage, a raceway arranged to deliver a staple with its legs extending longitudinally of the passage, means for advancing the staple through the button eye, and means for grasping the button eye and turning it in the direction of the passage. 105
9. In a machine of the class described, a raceway for fastening devices, a raceway 70 for attaching devices, said raceways converging, and a stop situated at the juncture of the raceways in the paths of both fastening and attaching devices delivered by the raceways. 110
10. In a machine of the class described, a raceway for fastening devices, a raceway for attaching devices, and a stop situated in the paths of both fastening and attaching devices delivered by the raceways and having a portion movable out of said paths independently of the other portions of the stop. 115
11. In a machine of the class described, a raceway for fastening devices, a raceway 85 for attaching devices, a stop situated in the paths of both fastening and attaching devices delivered by the raceways and having a portion movable out of said paths, and means for reciprocating said portion. 90
12. In a machine of the class described, a raceway for fastening devices, a converging raceway for attaching devices, and a rotatable stop situated at the juncture of the raceways in the paths of both fastening and attaching devices delivered by said raceways. 95
13. In a machine of the class described, a raceway for fastening devices, a converging raceway for attaching devices, and 100 a rotary and reciprocatory stop situated in the paths of both fastening and attaching devices delivered by the raceways. 105
14. In a machine of the class described, a raceway for fastening devices, a converging raceway for attaching devices, and a stop arranged for engagement by the devices from both raceways and provided with means for grasping one of said devices. 110
15. In a machine of the class described, a raceway for fastening devices, a converging raceway for attaching devices, and a rotary stop extending across the paths of devices from both raceways and provided with means operable in the rotation of the stop for grasping one of the devices. 115
16. In a machine of the class described, a raceway, a rotary and reciprocatory stop 120 co-operating with the raceway, and means arranged to reciprocate the stop along its axis of rotation. 125
17. In a machine of the class described, a raceway, movable means for advancing objects delivered by the raceway, and a stop for the objects co-operating with the raceway and having a portion movable independently of the remainder of said stop into and out of the path of the advancing means. 130

18. In a machine of the class described, a button raceway, a staple raceway, and a button stop co-operating with the button raceway and having a portion extending 5 into the path of the staple-yokes.
19. In a machine of the class described, a button raceway, a staple raceway, a button stop co-operating with the button raceway and having a movable portion extending 10 into the path of the staples in the staple raceway, and means for moving said portion out of the path of the staples independently of the button-engaging portion.
20. In a machine of the class described, 15 a button raceway, a staple raceway, and a stop device arranged to co-operate with the buttons and staples delivered by the raceways and having rotary and reciprocatory elements.
21. In a machine of the class described, 20 a button raceway, a staple raceway, and a co-operating button stop having a portion arranged to pass between the legs of a staple and engage said staple.
22. In a machine of the class described, 25 a button raceway, a staple raceway, a co-operating button stop having a portion arranged to pass between the legs of a staple and engage said staple, and means for moving said portion out of engagement with the button and staple.
23. In a machine of the class described, 30 button-supplying means, a device organized to grasp by the eye a button delivered by the supplying means, and means arranged to move the device to turn the thus-grasped button about the axis of its eye and head.
24. In a machine of the class described, 35 a button-raceway, a shifting device co-operating with the raceway and provided with a slot having opposite walls movable relatively to each other and arranged to receive a button eye, and means for moving the shifting device out of active co-operation with 40 the raceway.
25. In a machine of the class described, 45 button-conveying passages, a button-shifting device co-operating with the passages and provided with relatively movable walls between which a button eye may be grasped, and means arranged to move the shifting device to change the relation of the grasped button-eye to the passages.
26. In a machine for attaching buttons by 50 staples, a movable staple driver, means for moving a button with an associated staple to a position for driving said staple and including an element contacting with and movable in the positioning of the button and lying normally in the path of the driver, and means for imparting bodily movement to said element to carry it out of the path of 55 the driver.
27. In a machine of the class described, 60 button and staple raceways, means for advancing the buttons and staples from the raceways, a movable device having spaced sections with the space normally co-operating with one of the raceways, and means for moving the device to align its space with 65 the advancing means.
28. In a machine of the class described, button and staple raceways, means for advancing the buttons and staples from the raceways, a movable device having spaced 70 sections with the space normally co-operating with one of the raceways, one of the sections being movable relatively to the other, and means for moving the device to align its space with the advancing means.
29. In a machine of the class described, 75 button and staple raceways, means for advancing the buttons and staples from the raceways, a movable device having spaced sections with the space normally co-operating 80 with one of the raceways, one of the sections being movable relatively to the other, means for moving the device to align its space with the advancing means, and means for causing relative movement of the 85 sections.
30. In a machine of the class described, button and staple raceways, means for advancing the buttons and staples from the raceways, a movable device having spaced sections with the space normally co-operating 90 with one of the raceways, means for moving the device to align its space with the advancing means, and a member movable out of and into the space between the 95 sections.
31. In a button-attaching device, button 100 and staple raceways, a stop device co-operating with the raceways and including a rotatable spindle, a sleeve section rotatable with the spindle, and a co-operating sleeve section mounted to rotate with and relatively to the companion sleeve section.
32. In a button-attaching device, button 105 and staple raceways, a stop device co-operating with the raceways and including a rotatable spindle, a sleeve section rotatable with the spindle, a co-operating sleeve section mounted to rotate with and relatively to the companion sleeve section, and a friction device engaging said co-operating sleeve section.
33. In a button-attaching device, button 110 and staple raceways, a stop device co-operating with the raceways and including a rotatable spindle, a sleeve section rotatable with the spindle, a co-operating sleeve section mounted to rotate with and relatively to the companion sleeve section, a friction device engaging said co-operating sleeve section, and means for reciprocating the 115 spindle through the sleeve sections.
34. In a machine of the class described, 120 supplying means for fastening devices and attaching devices therefor, a single member 125

for advancing pairs of devices from the supplying means, and means for imparting to said member plural advancing movements for each pair of devices.

5 35. In a machine of the class described, supplying means for fastening devices and attaching devices therefor, reciprocatory means for advancing pairs of devices from the supplying means, means for imparting a 10 plurality of reciprocations to the advancing means for each pair of devices, and positioning means acting upon the devices between such plural reciprocations.

15 36. In a machine of the class described, supplying means for fastening devices and attaching devices therefor, means movable to assemble a supplied fastening device and an attaching device, and means for imparting an independent movement to the assembling means to cause the advance of the 20 assembled devices.

25 37. In a machine of the class described, supplying means for fastening devices and attaching devices therefor, a movable member co-operating with the supplied devices, and means for moving said member to assemble a fastening device and an attaching device, to withdraw it to free the devices and to thereafter advance the assembled 30 devices.

35 38. In a machine of the class described, supplying means for fastening devices and attaching devices therefor, a member for advancing pairs of devices from the supplying means, means for imparting to said member plural advancing movements for each pair of devices, and means for preparing one of the devices for its advance between the advancing movements.

40 39. In a machine of the class described, supplying means for fastening devices and attaching devices therefor, a movable member co-operating with the supplied devices, means for moving said member to assemble 45 a fastening device and an attaching device, to withdraw it to free the devices and to thereafter advance the assembled devices, and means for moving one of the devices during the withdrawal of the assembling 50 means.

40. In a machine of the class described, button and staple raceways, a co-operating staple-advancing member, and means for imparting to the advancing member a staple and button assembling reciprocation and thereafter a reciprocation by which the assembled staple and button are advanced.

41. In a machine of the class described, button and staple raceways, a co-operating staple-advancing member, and means for moving the member to partially advance a staple from its raceway to withdraw the member and to fully advance the staple.

42. In a machine of the class described, 45 a button raceway, a staple raceway, a mem-

ber arranged to contact with a staple delivered by the staple raceway, and means for moving the member to cause a staple leg to enter a button eye, to free the staple and button and to advance the assembled button 70 and staple.

43. In a machine of the class described, button and staple raceways, a co-operating staple-advancing member, means for moving the member to assemble a button and staple, 75 to withdraw the member and to fully advance the staple, and means for moving the button during the withdrawal of the advancing member.

44. In a machine of the class described, 80 button and staple raceways, a staple-advancing member co-operating therewith, a mechanism arranged to operate the member to introduce a staple into a button eye, and a mechanism arranged to operate the member 85 to advance the staple and associated button.

45. In a machine of the class described, button and staple raceways, a staple-advancing member co-operating therewith, a mechanism arranged to operate the member to 90 introduce a staple into a button eye, and a mechanism arranged to operate the member to advance the staple and associated button, said mechanisms acting at different speeds.

46. In a machine of the class described, 95 button and staple raceways, a staple-advancing member co-operating therewith, a mechanism arranged to operate the member to introduce a staple into a button eye, a mechanism arranged to operate the member to advance the staple and associated button, and connections between the mechanism and advancing member including provision for lost motion.

47. In a machine of the class described, 100 button and staple raceways, a staple-advancing member co-operating therewith, a mechanism arranged to operate the member to introduce a staple into a button eye, a mechanism arranged to operate the member to 110 advance the staple and associated button, connections between the mechanism and advancing member including provision for lost motion, and means acting upon the operating mechanism and tending to take 115 up the lost motion.

48. In a machine of the class described, a staple-advancing bar, an operating shaft therefor, and a plurality of actuators arranged to rotate the operating shaft at periods respectively predetermined in the operation of the machine.

49. In a machine of the class described, a staple-advancing bar, an operating shaft therefor, a power-shaft, and a plurality of 125 actuators connected to the power-shaft and operating shaft and arranged to exert their effects independently upon the latter.

50. In a machine of the class described, a staple-advancing bar, an operating shaft 130

therefor comprising independently movable sections, and a plurality of actuators connected to the sections.

51. In a machine of the class described, a staple-advancing bar, an operating shaft therefor comprising independently movable sections, a plurality of actuators connected to the sections, and connections between the actuators and shaft sections including provision for lost motion.

52. In a machine of the class described, converging button and staple raceways, a guideway to which they deliver, an advancing member movable in the direction of the guideway, and a movable stop device co-operating with the ways for engagement with both the buttons and staples and having a portion lying normally in the path of the advancing member.

53. In a machine of the class described, converging button and staple raceways, a guideway to which they deliver, an advancing member movable in the guideway, a movable stop device co-operating with the ways and having a portion lying normally in the path of the advancing member, and means for moving the advancing member to thrust a staple leg through the eye of a button held by the stop device.

54. In a machine of the class described, converging button and staple raceways, a guideway to which they deliver, an advancing member movable in the guideway, a stop device co-operating with the ways and having a reciprocatory portion lying normally in the path of the advancing member, and means for moving the stop device to align the button eye with the guideway.

55. In a machine of the class described, converging button and staple raceways, a guideway to which they deliver, an advancing member movable in the guideway, a movable stop device co-operating with the ways and having a portion lying normally in the path of the advancing member, means for moving the advancing member to thrust a staple leg through the eye of a button held by the stop device, and means for moving the stop device to align a button eye with the guideway.

56. In a machine of the class described, converging button and staple raceways, a guideway to which they deliver, an advancing member movable in the guideway, a movable stop device co-operating with the ways and having a portion lying normally in the path of the advancing member, means for moving the advancing member to thrust a staple leg through the eye of a button held by the stop device and then withdrawing said advancing member, and means acting during such withdrawal to align the button eye with the guideway.

57. In a machine of the class described, converging button and staple raceways, a

guideway to which they deliver, an advancing member movable in the guideway, a rotatable stop device co-operating with the ways and having a portion lying normally in the path of the advancing member, and means for moving said portion independently of the rotation out of such path.

58. In a machine of the class described, converging button and staple raceways, a guideway to which they deliver, an advancing member movable in the guideway, a movable stop device co-operating with the ways and having a portion lying normally in the path of the advancing member, and means for moving the advancing member to thrust a staple leg through the eye of a button held by the stop device, for withdrawing the advancing member and for then producing a longer reciprocatory movement.

59. In a machine of the class described, converging button and staple raceways, a guideway to which they deliver, an advancing member movable in the guideway, a movable stop device co-operating with the ways and having a portion lying normally in the path of the advancing member, means for moving the advancing member to thrust a staple leg through the eye of a button held by the stop device, for withdrawing the advancing member and for then producing a longer reciprocatory movement, means for moving the stop device to align a button eye with the guideway, and means for removing a portion of the stop device from the path of the advancing member.

60. In a button-attaching machine, the combination with staple-setting mechanism, of opposite relatively movable members between which the work is held for the setting operation, yieldable means actuated in the operation of the machine for producing such movement to engage the work, and means movable into the path of one of the members for locking said members against separation during the setting operation.

61. In a button-attaching machine, the combination with staple-setting mechanism, of opposite relatively movable members between which the work is held for the setting operation, a driving shaft, yieldable connections between said shaft and one of the members for producing such movement to engage the work, means movable through different distances for locking the members against separation during the setting operation, and yieldable actuating means for the locking means.

62. In a button-attaching machine, a head, a staple-setting bar movable therein, a slide, an actuator for reciprocating the slide, an anvil fixed to the slide and movable into co-operation with the head, a spring interposed between the actuator and slide,

and a wedge co-operating with the slide to lock the anvil in co-operation with the head.

63. In a button-attaching machine, a head, a staple-setting bar movable therein, a slide, an actuator for reciprocating the slide, an anvil fixed to the slide and movable into co-operation with the head, a spring interposed between the actuator and slide,

a wedge co-operating with the slide to lock the anvil in co-operation with the head, an actuator for the wedge, and a spring interposed between said actuator and the wedge.

In testimony whereof I have signed my name to this specification.

ALBERT LATHAM.
